S. KASKOTO.
RAILROAD TIE AND CLAMP.
APPLICATION FILED JULY 19, 1918.

Patented Jan. 28, 1919.

By his Attorney

Inventor
Stephen Kaskoto

Chairman

UNITED STATES PATENT OFFICE.

STEPHAN KASKOTO, OF LANSING, MICHIGAN.

RAILROAD-TIE AND CLAMP.

1,292,796.

Specification of Letters Patent. Patented Jan. 28, 1919.

Application filed July 18, 1918. Serial No. 245,596.

To all whom it may concern:

Be it known that I, STEPHAN KASKOTO, a subject of the King of Hungary, residing at Lansing, county of Ingham, and State of Michigan, have invented certain new and useful Improvements in Railroad-Ties and Clamps, of which the following is a specification.

This invention relates to improvements in the construction of railroad ties and means for clamping the rails thereto.

The principal object of the invention is to provide a tie formed principally of concrete, in which are embedded reinforcing elements, together with means for holding the rails in their adjusted position.

Another object is to provide means which hold the rails in a secure manner, and finally, to provide means whereby the rails are resiliently supported so as to permit the same to yield when under extreme load thereby prolonging the life of the rail.

These and other like objects are attained by the novel construction and combination of parts hereinafter described and shown in the accompanying drawing, forming a material part of this specification, and in which:

Figure 1 is a fragmentary top plan view showing a section of railroad track made in accordance with the invention.

Fig. 2 is a vertical sectional view taken on line 2—2 of Fig. 1, through the center of a tie.

Fig. 3 is a similar sectional view of a modified form of tie.

Fig. 4 is a transverse sectional view taken on line 4—4 of Fig. 1, and

Fig. 5 is a similar transverse sectional view showing a modified form of spring support.

Referring now more particularly to Figs. 1, 2 and 4 of the drawings, the main portion of the tie 10 is shown to be composed of concrete in which are introduced a plurality of rods 11, 12, 13, the latter having upturned ends 14 which are firmly embedded within the tie.

This tie is so molded as to present undercut recesses 17 extending into the body toward the center of the tie, midway therein, which are adapted to engage the feet of

metallic clamp blocks 18, having outwardly projecting flanges 19, contactable with the lower flanges of track rails 20, while raised portions 21 of the tie 10 contiguous to the main recesses 22 are adapted to receive the outer blocks 25, having overhanging flanges 26, similar to the flanges 19, and adapted to make contact with the upper surface of the flanged bases of the rails 20.

Inserted in the ends of the ties 10 are the heads 27 of bolts 28 passing upward through the clamp blocks 25, and provided with clamp nuts 29 at the outer ends by means of which the clamps may be firmly pressed upon the flange of the rail, the rails being supported upon heavy springs 30, here shown to be helically wound and of sufficient strength to carry the rail, together with whatever load there may be superposed thereon.

The bottom coils of the springs 30 rest upon plates 31, having downturned ends 32, engageable with the outer surface of the tie 10. In the form shown more particularly in Fig. 3, the tie 35 is formed wholly of metal and provided with clamp blocks 36 secured within recesses 37, the recesses terminating in raised elements 38 formed with the tie, the clamp blocks being held therein by means of a clamp bolt 39, the end 40 of which extends upward so as to be conveniently operated.

The rails 20 are held in position by their lower base flanges contacting with flanges 42 formed with the body of the tie 35, at one side and with the blocks 36 upon the other side. Springs 30 rest upon blocks 31 having downturned edges 32 in the manner previously described.

In the modification shown in Fig. 5 a similar construction is observable except that the plates 40 upon which the springs rest are flat and may be driven out laterally from the tie, thereby decreasing the compression of the springs and permitting the rails to become free so that the bolts 40 may be readily removed.

Having thus described my invention, what I claim as new and desire to secure by Letters Patent, is.

A cement tie, having metallic reinforcing bars secured therein and containing under-

cut recesses, metallic blocks suited to said recesses, said blocks having overhanging flanges adapted to contact with the inner flange of the rail, removable blocks secured in said recesses, engageable with the opposite side of said rail, means for clamping

said removable blocks, spring supports below said rails, and seats upon which said spring supports rest.

In witness whereof, I have signed my name to this application.

STEPHAN KASKOTO.
